UNITED STATES PATENT OFFICE.

JAMES B. HUCKLE AND WILLIAM E. RIENHART, OF COLUMBUS, OHIO.

HOT-AIR FURNACE.

1,079,491.

Specification of Letters Patent. Patented Nov. 25, 1913.

Application filed July 19, 1913. Serial No. 779,941.

To all whom it may concern:

Be it known that we, JAMES B. HUCKLE and WILLIAM E. RIENHART, citizens of the United States, residing at Columbus, in the 5 county of Franklin and State of Ohio, have invented certain new and useful Improvements in Hot-Air Furnaces, of which the following is a specification.

Our invention relates to hot air furnaces 10 and aims to provide a structure particularly adaptable for use in connection with gas although not necessarily so.

In the embodiment of our invention we aim to provide a novel structure in the peculiar location of the burner or fire box and combustion chamber. We have placed the burner or fire box and combustion chamber in the upper portion of the furnace casing, the purpose of this being two-fold: 15 that of convenience in lighting, in that the burner will be in a more elevated position than usual and also in causing the products of combustion to pursue a downward movement in their passage to the chimney. This 20 downward movement is desirable in that the air to be heated is taken in adjacent the bottom of the furnace and is allowed to pass upward, thereby always coming into contact with portions of the furnace, in- 25 creasing in heat until it has reached the combustion chamber which is usually the hottest portion. We have also provided a novel arrangement of drums or radiators used by the products of combustion in trans- 30 ferring their heat to the incoming air.

The preferred embodiment of our invention is shown in the accompanying drawings, in which similar characters of reference designate corresponding parts, and 35 in which:

Figure 1 is a central vertical section of our furnace structure, Fig. 2 is a bottom plan view of the structure shown in Fig. 1, showing the outer casing removed, and, Fig. 3 45 is a section taken on line 3—3 of Fig. 1 and looking in the direction of the arrows.

In carrying out our invention, we have provided the usual type of casing 1 having an air inlet pipe 2 adjacent the base and 50 hot air outlet pipes 3 adjacent the top portion. It will also be noted that the top wall 4 of this casing is formed of sheet metal rolled to cone shape, the apex of which is centrally disposed with relation to the cas-

ing. The purpose of this will be referred 55 to hereinafter.

Within the casing and near the upper portion thereof, we have provided a combustion chamber 5 of peculiar construction to accommodate any preferred type of gas 60 burner 6. This combustion chamber is comprised of an inner circular wall 7 having an open top and an outer circular wall 8 having its top closed by an upwardly extending cone-shaped wall 9, the apex of this 65 latter cone being in vertical alinement with the apex of the cone 4. Leading downwardly from the combustion chamber 5, we have provided a number of pipe sections 10, these pipe sections converging toward each 70 other and communicating with a drum 11 located beneath the level of the combustion chamber and adjacent the base portion of the casing. It will be noted that these pipe sections enter the drum at approximately 75 a central point, thereby permitting the products of combustion to flow outwardly throughout its internal volume. This lower drum 11 is also provided with a plurality 80 of short pipe sections 12 disposed in circular array and being designed to permit the free upward passage of cold air entering through the pipe 2. From the lower drum 11, the products of combustion pass upwardly through conduits 13 disposed concentrically with the pipe sections 12, but along the periphery of the drum. It will 85 be noted that the side walls of the drum 11 are somewhat inclined to give a slight upward direction to the products of combustion and to prevent the creation of dead air 90 spaces. After leaving the conduits 13, these products enter a superposed angular drum 14 having its inner wall 15 inclined for a purpose similar to that outlined for the 95 lower drum. This superposed drum 14 is also provided with a plurality of short pipe sections 16 passing entirely therethrough to also permit the passage of cold air. It will 100 be noted that this superposed drum is 105 slightly larger than the lower drum, whereby the air entering through the short pipe sections 12 in the lower drum passes upwardly and impinges on the pipe sections 10 leading from the combustion chamber, while the pipe sections 16 in the upper drum permits the passage of air not before heated. The entire structure is supported from

an annular flange member 17 rigidly carried by the side of the casing, the horizontal leg of this flange member supporting the superposed drum 14 which in turn supports 5 the remaining structure.

From the description thus far given, it will be apparent that the products of combustion from the burner 6 enter the combustion chamber 5 and are carried downwardly 10 from this point, entering the lower drum 11 at approximately a central point. From here they spread over the surface of the drum and again pass upwardly through the conduits 13 into the upper drum 14. In 15 the meantime, cold air enters through the pipe 2 and becomes heated by contact with the walls of the lower drum and in its passage through the pipe sections 12, where it again comes in contact with the heated pipes 20 10 and the combustion chamber itself. A portion of the incoming air is also caused to engage the walls of the upper drum and passes upwardly through the pipe sections 16, becoming heated during its entire passage. It will be noted that as the air rises, 25 it continually comes in contact with surfaces warmer than itself and consequently a maximum amount of heat will be extracted from the products of combustion. Finally, this 30 heated air is allowed to collect in the upper portion of the chamber and to avoid dead air spaces or pockets, we have resorted to the peculiar cone construction heretofore described. The cone shaped upper portion of 35 the combustion chamber gives a confining space for the products of combustion, as well as increasing the amount of radiating surface of the chamber itself. The two cones 4 and 9 are brought adjacent each 40 other to deflect the heated air toward the outer portion of the casing, from where it is drawn off through the outlet pipes 3. The upper drum 14 is also provided with a 45 pipe 18 connected thereto in any desired manner to form a connecting means for the cooled products of combustion to the chimney. It is to be understood that we desirably use this construction in connection with 50 gas furnaces, although it is possible by a slight modification to use the same with coal or similar fuel. In its use with any type of fuel, it sometimes becomes desirable to create a direct draft or to regulate in a manner the draft through the main flue.

This may be accomplished by the interposition of short pipe sections 19 having a damper 20 therein and connecting the main outlet pipe 18 and the combustion chamber 5 as indicated in Fig. 1.

It will be noted that we have shown only 60 three pipe sections 10, it being deemed sufficient for the purposes of illustrating our invention to show only this number, although it is to be understood that any desired number 65 may be used that may be convenient, especially as regards the fire box door, etc.

What we claim, is:

1. A hot air furnace comprising a casing, a combustion chamber in the top of said casing, pipes leading downward from the top 70 of said chamber, a drum below the level of the bottom of said combustion chamber, said pipes converging toward each other and entering said drum at approximately its center, a second drum above said first drum, 75 conduits connecting said drums, an outlet pipe connected to said second drum, and means for introducing air to be heated beneath said first drum.

2. A hot air furnace comprising a casing, 80 an inwardly extending cone forming the top of said casing, a combustion chamber in the top of said casing, an upwardly extending cone forming the top of said chamber and lying directly beneath said casing top, 85 pipes leading downward from the top of said casing, a drum below the level of the bottom of said combustion chamber, said pipes converging toward each other and entering said drum at approximately its center, 90 short pipe sections extending through said drum to permit the free passage of air, a second drum above said first drum, conduits from the periphery of said first drum leading to said second drum, short 95 pipe sections extending through said second drum to permit the free passage of air, an outlet pipe connected to said second drum, and means for introducing air beneath said first drum.

In testimony whereof we affix our signatures in presence of two witnesses.

JAMES B. HUCKLE.
WILLIAM E. RIENHART.
